DUAL-ACTION SHOE ARCH

Karl J. Patry, Baltimore, Md.

Application July 13, 1946, Serial No. 683,499

2 Claims. (Cl. 36—76)

1

This invention refers to footwear and more particularly to the conventional types of shoes or boots.

It is an object of this invention to provide a new and improved type of shoe that will avoid one or more of the disadvantages and limitations of the prior art.

Another object of the present invention is to provide a new and improved shoe that will afford support of the arch of the foot of the user, without being in direct contact thereto, and without reducing the foot space within the shoe.

An additional object of the herein described invention is to provide a new and improved shoe that will afford a cushion to the ball portion of the foot of the user that will provide comfort to him.

Another object of this invention is to provide a dual action arch support which supports the metatarsal joints and foot arch.

Other objects of this invention are more fully set forth.

For a clearer understanding of the invention reference is made to the appended drawings and following description, which together illustrate a particular form of the invention by way of example, while the claims point out the particular scope of the invention.

Referring to the drawings, in which:

Figure 1 is a view looking at the bottom of the sole of a shoe embodying this invention;

Figure 2 is a side view of the shoe indicated in Figure 1;

Figure 3 is a detail of an arch support in the embodiment, and

Figure 4 is a detail of an arch support shown in Figure 3.

Similar references pertain to similar portions in the various drawings.

A conventional low-cut shoe 10 for a person, has the usual sole 11 and heel 12 attached to it, with a thin shank section 13 in between. Where the sole terminates at the upwardly curved shank section, exteriorly, there is attached a percussion pad of resilient material which is partly elliptical in peripheral contour.

The pad may be attached by cement, sewed on, or tacked, as may be suitable. This section is preferably in one integral piece but with two operating parts 14 and 15 having a V-like groove 16 in between. The piece 15 is bevelled on the side 17 towards the heel. The section extends from the sole portion towards the shank, and while its upper surface 18, follows the contour of the shank section 13, its lower surface 19 is hori-

2

zontal with the bottom surface of the sole 11. A diaphragm 20 of flexible fabric is preferably used on the upper surface 18 of the pad section to reinforce it and afford means for attaching it to the shoe and otherwise manipulating it. The rear side 17 of the piece 15 is preferably angular to prevent dirt from accumulating thereto.

When a person uses a shoe of this kind, the action of the shoe in walking is one of bending 10 forcibly with the heel rising and the toe portion on the terrain, to start with. Then the heel during the next step, contacts the ground first with the sole following, and following the bending action described previously. The pad section is 15 therefore in operation most of the time during the step, because it is located at approximately the middle. The section, being transversely grooved, acts like a hinge as the heel rises. The section contacts the terrain gently, and prevents 20 the shank from looping down and forcing the foot of the user to bend convexedly. This form of bending of the foot is the basis for a number of foot ailments, that are orthopedically and experimentally treated by employing arch supporters and other mechanical appliances placed 25 within the shoe. The appliances take up room thereby limiting the movements of the foot and by reason of their rigidity weaken and injure the foot structure more. The pad provided by this 30 invention exterior to the shoe, avoids interference with foot expansion, contraction and bending desirable for the proper exercise of the foot, but avoids the excessive stress which the 35 shoe itself can artificially produce, when the shank "gives" while the toe and heel portions are rigid. The arch of the foot is concavely formed and should retain that shape, but the conventional shoe has a tendency to strain it to a convexed form. The invention prevents this, without 40 preventing the shoe from flexing in a normal manner. As mentioned this device causes the shoe to properly support the metatarsal joints and the foot arch and at the same time allow the 45 shoe and foot to bend readily.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the 50 appended claims.

Having thus described the invention, what is claimed is:

1. A percussion pad section of the class described comprising a forward portion and a rearward portion integrally connected and having a groove running transversely across the under face thereof affording a hinge between the said portions, the upper face of said portions being shaped to follow the contour of a shoe at the shank thereof for attachment thereto, and said portions having their under face parallel to the sole and heel of the shoe when in place. 10

2. A percussion pad section of the class described comprising a forward portion and a rearward portion integrally connected and having a groove running transversely across the under face of the pad at the junction of said portions thereby affording a hinge between said portions, the upper face of said portions being shaped to follow the contour of a shoe at the shank thereof for attachment thereto, said portions having 15 20

their under face parallel to the sole and heel of the shoe when in place and also having tapered sides from the points of attachment on the shoe, to the under face of said portions. 5
